UNITED STATES PATENT OFFICE.

PAUL M. PAMPERIN, OF LA CROSSE, WISCONSIN.

SHIRT.

Application filed October 29, 1923. Serial No. 671,324.

To all whom it may concern:

Be it known that I, PAUL M. PAMPERIN, a citizen of the United States, and resident of La Crosse, in the county of La Crosse and 5 State of Wisconsin, have invented a certain new and useful Improvement in Shirts, of which the following is a full, clear, concise, and exact description, reference being had to the accompanying drawings, forming a 10 part of this specification.

My invention relates to improvements in shirts including boys' blouses, and particularly in the so-called coat shirts, one object of the invention being to prevent the annoying 15 tendency of the overlapped edges at the front of a snugly fitting shirt to spread apart between the buttons just above the belt line.

Another object of my invention is to prevent the shirt from "working up" at the 20 belt line by presenting a smooth fitting surface across the abdomen.

Other objects, features and advantages of my invention will appear from the appended claims, from the following description thereof, and from the accompanying drawings herein referred to, in which—

Figure 1 illustrates a shirt to which my invention has been applied, the bandage or 30 flap member being shown in dotted outline;

Figure 2 is a detail of the lower front side of the shirt, the overlapping side of the shirt being folded back, and

Figure 3 is a transverse section taken on 35 the line 3—3 of Figure 2.

In Figure 1, I have shown a shirt 10 of the coat type, that is, where the shirt buttons at the front through the entire length thereof, the edge 11 of the underlying side of the shirt being reinforced by the tape 11' or otherwise, to provide for the securing of the usual spaced buttons 12—12. The other, or 40 overlying side 13, of the shirt is provided at its edge with the usual hem forming a buttonhole strip 14, the buttonholes of which co-operate in the usual manner with the buttons 12.

A reinforcing flap 15 of inexpensive but 45 strong material, such as muslin, cut to a triangular shape, is placed with its base along the underlying edge or button strip 11 and is sewn at the back thereof by the parallel stitchings 16 and 16 which are used to form the hem of and secure the reinforcing tape 11' to the button strip 11, whereby a secure 50 anchorage of the piece 15 is obtained be-

tween two adjacent buttons 12 and preferably beyond each of the buttons so that the total extent of the securement is substantially twice the distance between two buttons. 60 As shown in Figure 1, this piece 15 extends principally above the belt line and a small distance below the belt line.

Adjacent its triangular apex, the piece 15 is provided with a button hole 17 which is 65 adapted to cooperate with a button 18 secured at the inner side of the overlying side 13 of the shirt. It is apparent that when the buttons along the button strip are buttoned and the button 18 engages the button-hole 17, that the horizontal strain across the 70 front of the shirt will be borne not only by the buttons 12, as is usual, but also by the button 18, the latter being so positioned that it distributes the strain on the button strip 75

11 over a considerable distance along the strip, as represented by the base of the piece 15. In this way, the buttonhole strip 14 is relieved of the localized strain at the button holes which would otherwise tend to form 80 horizontal wrinkles across each buttonhole. If the reinforcing piece 15 were not used, the buttonhole strip 14 intermediate the buttonholes would be pulled apart so that the shirt would "pop" open at these points. 85 With my construction, however, the major portion of the horizontal strain adjacent the belt line is borne by the button 18, through the reinforcing piece 15 relieving the buttonhole strip 14 in this vicinity of most of 90 its pulling strain. If any wrinkles are then formed, they will be at the side of the shirt and in the opposite direction from the button 18, where they will not be visible.

An added advantage in the use of this reinforcing piece 15 is that it forms a bandage-like surface across the abdomen which is 95 smooth fitting, with the result that it effectively aids in preventing the shirt from "working up" from the belt during any exercising by the wearer. Were the bandage piece 15 not present, the sharp horizontal wrinkles or creases formed across the buttonholes would not present a smooth fitting 100 surface across the abdomen, with the result that the shirt is much more easily pulled upwardly and out of place than when the surface around the belt line is kept smooth fitting and without wrinkles. The advantages of such a construction permit of the 105 wearing of a more tightly fitting shirt and is especially desirable as an athletic shirt in 110

general, and is particularly advantageous in shirts for more corpulent men.

While I employ the terms shirt and coat shirt, it is to be understood that I intend 5 thereby to include boys' blouses and other similar garments in which the features of my invention may be embodied.

Having thus described my invention, what I claim is new and desire to secure by Letters Patent of the United States is:

1. The combination with a coat shirt having buttons along one front edge thereof and co-operating buttonholes along the other and overlapping edge thereof, of an auxiliary abdominal bandage, one end of which is sewn along said button edge, said bandage extending beyond said button edge and beneath the overlapping side of said shirt, the opposite end of said bandage and an inwardly spaced point on said overlapping side being provided with co-operating fastening means for preventing the spreading apart of said two edges between two of said buttons on said button edge and for tending to prevent said shirt from working up at the waist line by presenting a smooth fitting surface across the abdomen.

2. The combination with a coat shirt having a button strip and a buttonhole strip overlapping said button strip, of an auxiliary abdominal bandage of triangular shape, the base of said bandage being sewn to and along said button strip adjacent the waist line to extend between two buttons, the apex of said bandage extending beneath the overlapping side of said shirt, and a co-operating button and buttonhole on said bandage near the apex thereof and on said

overlapping side, for the purpose of providing a smooth fitting abdominal bandage 40 which prevents spreading of said two flaps intermediate the buttons and tends to prevent the shirt from working up at the waist line.

3. The combination with a coat shirt having 45 buttons along one front edge thereof and buttonholes along the other and overlapping edge therefor for co-operating with said buttons, of a separate piece of fabric, one end of which is sewn to said shirt along said button edge, and the other end of which is provided with fastening means which co-operates with fastening means on said buttonhole side of the shirt at a distance spaced 50 away from said buttonhole edge for the purpose of preventing a spreading of said two edges at a mid point between buttons on said button edge.

4. The combination with a coat shirt having 55 co-operating fastening means on the respective overlapped edges thereof, of a piece secured at one end to one of said edges and extending under the opposite side of the shirt, the other end of said piece and said 60 opposite side being provided with co-operating fastening means at a point spaced from said overlapped edges for the purpose of preventing a spreading of said edges between said first mentioned fastening means.

In witness whereof, I hereunto subscribe 65 my name this 25th day of Oct., 1923.

PAUL M. PAMPERIN.

Witnesses:

EDWARD C. STRY,
VICTORIA BESL.
